DESIGN FOR A DRESS

Marie Pono, New York, N. Y.

Application December 4, 1937, Serial No. 73,367

Term of patent 3½ years

To all whom it may concern:

Be it known that I, Marie Pono, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged view of one of the embroidered elements appearing on the dress shown in Fig. 1.

The characteristic feature of my design resides in the combination on the dress disclosed of the specific embroidery on the skirt, blouse and sleeve portions as shown.

I claim:

The ornamental design for a dress substantially as shown and described.

MARIE PONO.
